UNITED STATES PATENT OFFICE.

CLARA ALBERTA DON, OF LONDON, ENGLAND, ASSIGNEE TO FRANCES MAUD COUSINEAU, OF TORONTO, ONTARIO, CANADA, AND LONDON, ENGLAND.

BRUSH.

Application filed February 9, 1923. Serial No. 617,987.

To all whom it may concern:

Be it known that I, CLARA ALBERTA DON, a subject of the King of Great Britain, residing at 15 Upper Bedford Place, London, 5 W. C. 1, England, have invented certain new and useful Improvements in or Relating to Brushes, of which the following is a specification.

This invention has reference to brushes 10 of the kind in which the operative portion (corresponding to the bristles of an ordinary brush) is formed of india-rubber.

As usually made these brushes have the operative portion formed by moulding, but 15 in carrying out this invention moulding is dispensed with and the operative portion of the brush is formed of thin india-rubber or elastic thread cut to suitable lengths.

Thus according to the invention, the said 20 operative portion consists of short lengths or strands of very flexible india-rubber or elastic thread (as distinguished from moulded projections) which are doubled or folded over and have the bend or loop inserted in, or passed through, holes in a suitable hard or rigid holder, backing or stock, of wood, bone or ebonite for instance, 25 analogous to the back of an ordinary brush.

These short lengths or strands are retained 30 in position by cotton or other threads, cords or their equivalent passed transversely through the loops or bends. They are, conveniently, arranged in groups, bunches or tufts, each secured in its own hole or 35 cavity in the back or stock, and may be combined with bristles or hair such as used in ordinary brushes, if desired, although for most purposes rubber or elastic strands alone are found satisfactory.

40 The holes in which the rubber or elastic strands are secured, may be small enough to nip or compress the strands, these latter being passed into them in a stretched condition so that when let go and allowed to 45 expand they are gripped in the holes.

The invention is applicable to all kinds of brushes, for instance clothes-brushes, bath or massage brushes, shaving brushes, and brushes for general household or domestic 50 purposes. It may also be applied to revolving brushes in carpet-sweepers or even in machinery, for instance in the textile trades for brushing machines in velvet, cloth, or cotton manufacture for instance. 55 In fact brushes may be made according to

this invention for any purposes for which ordinary brushes with soft bristles or fibres are used.

In order that the invention may be clearly understood and readily carried into effect 60 reference will now be had by way of example to the accompanying drawings, in which:—

Fig. 1 is a section on the line 1—1 (Fig. 2) of one form of brush, analogous to an 65 ordinary hand brush or bath brush.

Fig. 2 is a plan of the back or stock of the brush, with its cover-piece taken off, to show how the looped strands are retained in position.

Figs. 3, 4 and 5 are diagrams to a larger scale illustrating one mode of threading the bent rubber or elastic strands into the holes in the back, as hereinafter referred to.

Fig. 6 shows one of the bent or folded 75 strands before it is inserted in the back.

Fig. 7 is a side-view of a construction of shaving brush according to the invention.

Fig. 8 is a separate plan view of the holder or cap-piece in which the strands of 80 the brush itself are secured.

a a represent the india-rubber or elastic strands, which are cut to the requisite length to form the operative portion of the brush. These strands are secured in the back or 85 stock *b*, their free tips or points *c* forming the face of the brush as it were. They may be made up in pairs by bending or folding over a thin piece of rubber or "elastic" thread (of the ordinary square form in 90 cross-section) to the shape shown in Fig. 6, the top fold or bend (at *a*¹) being secured in suitable holes *d* in the back or stock *b*.

These holes may be so formed, for instance by making them taper as shown, that 95 they are smaller at the end from which the strands *a* project, thus nipping and holding the strands more effectually and assisting in keeping them in position.

The actual fixing or securing of the cut 100 strands *a* is ensured by retaining means such as backing threads or cords *e* drawn transversely through the bent or looped part *a*¹ behind the back of the brush, as will be obvious from the drawings.

These improved brushes may of course be made by machinery in any convenient way, but in making them by hand the following simple plan may be adopted:—In order to 110 secure the loops *a*¹ in the holes *d* of the back

or stock the retaining thread *e* is drawn in a loop through one of these holes by means of a hook *f*, as in Fig. 3. Through this loop one or more of the strands *a* can be readily inserted and folded (Fig. 6) so that the bends or loops of each are linked into one another as in Fig. 4. Then by pulling back the thread or cord *e*, the rubber can be stretched out until its loops *a*¹ easily pass through the hole *d* (see Fig. 5), whereupon on letting go the strands *a*, the elastic will swell or expand to its natural thickness and so grip in the bottom of the hole *d*. Two or more strands may thus be drawn at the same time into each hole, forming a group or tuft of free ends projecting therefrom. The backing or retaining thread or cord *e* is finally drawn straight and tight across the back of the brush (see Fig. 2) and knotted or otherwise secured in any convenient way, after which the outer (or finishing) cover *b*¹ of the back is secured in place.

When applied to a shaving brush as in Figs. 7 and 8, exactly the same system may be followed, the cut strands *a*, being secured in a small disc or cap *b*² which is screwed into a socket or shank *b*³. The holes *d* in which the strands or tufts are secured may be in this case arranged approximately concentrically so that one single fixing thread *e* can be carried round through all of them. They are also inclined or more or less radial to the rounded face of the disc or cap *b*², thus allowing the brush strands to spread out all round as indicated.

For the sake of clearness, part of the

strands are omitted in Figs. 7 and 8, only a few being shown to illustrate their arrangement.

As before mentioned the improved brush is clearly distinguished from brushes of the kind in which the operative portion consists of prongs, fingers or fibres moulded or secured on a rubber or fabric backing. Moreover it is not necessary that the brush should have only rubber strands, as ordinary fibres or bristles can be used in combination with the elastic, and distributed in alternating rows or as may be convenient.

Obviously the invention can be modified in various ways in carrying the same into practice, without departing from the general nature thereof.

I claim:—

1. In a rubber brush, the combination of cut elastic strands formed into loops, a backing with taper holes adapted to nip and compress the loops, retaining cords passed transversely through the loops behind the backing, and an outer cover applied over the back of the brush, substantially as described.

2. In a rubber brush, the combination of elastic strands cut to the requisite length and formed into loops, a backing in which said loops are held and nipped tightly at the part where they enter the backing, a cord threaded successively through the loops behind the backing; and a cover for the back of the brush, substantially as described.

In testimony whereof I affix my signature.

CLARA ALBERTA DON.
